UNITED STATES PATENT OFFICE.

JOHN EARL GREENFIELD, OF EL CENTRO, CALIFORNIA.

WEED DESTROYER.

Application filed February 18, 1922. Serial No. 537,524.

To all whom it may concern:

Be it known that I, JOHN EARL GREENFIELD, a citizen of the United States, residing at El Centro, in the county of Imperial and State of California, have invented new and useful Improvements in Weed Destroyers, of which the following is a specification.

This invention relates to devices for removing vegetation from irrigation and drainage ditches, and has for its object the provision of a novel truck carried device whereby a powerful blast of flame may be directed upon weeds or other vegetation growing in irrigation and drainage ditches, whereby to effect destruction thereof and leave the ditches in proper condition for the free passage of water therethrough.

An important object is the provision of a device of this character which includes a blower which is associated with a movable outlet pipe which carries burners which direct a blast of flame to the desired points, the outlet pipe of the blower having associated therewith means for feeding fuel thereto for producing the highly combustible mixture supplying the burners.

Another object is the provision of a device of this character having novel means for adjusting the burners with respect to the blower and the ground so that the device may be efficiently used in deep or shallow ditches or upon an incline.

An additional object is the provision of a device of this character which will be comparatively simple and inexpensive in construction and installation, which may be used in association with an ordinary truck or tractor, which will be highly efficient and durable in service and a general improvement in the art.

With the above and other objects and advantages in view, the invention consists in the details of construction to be hereinafter more fully described and claimed, and illustrated in the accompanying drawings, in which:

Figure 1 is a plan view of my device associated with a supporting vehicle;

Figure 2 is a side elevation;

Figure 3 is a detail cross sectional view on the line 3-3 of Figure 1; and

Figure 4 is a fragmentary elevation showing the gearing for moving the burner pipe.

Referring more particularly to the drawings, the letter A designates a suitable supporting vehicle which may be a truck,

tractor or the like, or which may be merely a wagon drawn by any preferred means. In the latter case it would be necessary to provide an engine B suitably mounted upon the wagon, though in case the device is used upon either a truck or tractor power would be taken from the motor thereof in an obvious manner.

In the further carrying out of my invention I provide a blower 10 of the centrifugal type having an air inlet 11 at its center and a tangentially disposed outlet pipe 12 upon the end of which is rotatably mounted one end of an elbow 13 with the other end of which is connected a pipe 14 terminating in an elbow 15 which is connected with a burner structure including two or more branches 16. The numeral 17 designates a fuel supply tank, the fuel most adapted for use being gasoline, and leading from this tank are pipes 18 which extend to the outlet pipe 12 of the blower and are provided with control valves 19 which regulate the passage of the fuel into the outlet pipe of the blower.

The elbow 13 is necessarily of a flexible nature and is preferably of the telescopic type, that is to say the various sections 13^a thereof must be capable of relative movement in a telescopic manner to permit the pipe 14 to be moved up and down. To brace the structure, the pipe 12 is encircled by a collar 13^b with which is hingedly connected at 13^c a collar 13^d which encircles the pipe 14. It is the connection of the members 13^b and 13^d which constitutes the pivot, the function of the elbow proper being merely to form a proper conduit.

Carried by the elbow 13 is a gear ring 20 with which meshes a worm 21 moved by a hand wheel 22. By turning this hand wheel and consequently the worm, it will be seen that the elbow 13 carrying the pipe 14 and the burners may be swung to one side or the other of the vehicle and may also be swung into a more or less inclined position whereby to bring the ends of the burner branches 16 into the proper relation to the ground for the purpose of burning weeds or other matter thereon. The numeral 23 designates an upright carrying a pulley 24 about which is trained a flexible member 25 such as a cable or the like and which is suitably connected with the pipe 14 for raising and lowering the same.

In the operation of the device the vehicle A which supports my burner structure is

drawn along the ground beside the ditch to be burned out. The blower 10 is driven from the engine B by any suitable means, such as the belt and pulleys shown, and the gasoline or other fuel is admitted through the valves 19, the supply being readily controllable thereby. The mixture of gas and air issuing from the burners 16 must of course be ignited which may be accomplished in a simple manner and it will be apparent that there will be a powerful blast of flame issuing from the burners which will very efficiently operate to burn up entirely any weeds, grass or other matter within the ditch. By properly manipulating the hand wheel 22 and the cable 25 it will be seen that the position of the burners may be varied so as to reach down into ditches regardless of whether the sides be steep or sloping. It will be observed that the burner structure is capable of being swung from one side to the other so that a ditch may be properly burned out from either side thereof and regardless of the direction of travel of the vehicle A.

From the foregoing description and a study of the drawings, it will be apparent that I have thus provided a simply constructed and easily controlled device which will be a great time and labor saver in obviating the strenuous manual labor involved in removing weeds from irrigation or drainage ditches under the present system. Owing to the simplicity of construction and fewness of the parts it will be apparent that there is nothing to get out of order and

that the device should consequently have a long life and satisfactorily perform all the functions for which it is intended.

While I have shown and described the preferred embodiment of the invention, it is of course understood that I reserve the right to make such changes in the form, construction and arrangement of parts as will not depart from the spirit of the invention or the scope of the subjoined claim.

Having thus described my invention, I claim:

In a device of the character described, a wheeled frame, a blower mounted thereon and having a vertical outlet pipe, power means on the frame for driving the blower, an elbow including a base section rotatable upon said blower outlet and equipped with a gear, the elbow further including a plurality of telescopically connected sections, an L-shaped pipe connected with the elbow and carrying branches constituting burners, a plurality of valved fuel inlet jets mounted upon the blower outlet and discharging thereinto, a supporting bracket structure carried by the blower outlet, a worm journaled in said bracket and meshing with said gear for effecting rotary adjustment of said pipe carrying the burners, and a flexible member connected with the pipe and trained over a guide and operable for swinging said pipe to vary the height of the burners with respect to the ground.

In testimony whereof I affix my signature.

JOHN EARL GREENFIELD.
